UNITED STATES PATENT OFFICE.

AXEL G. ANDERSON, OF JAMESTOWN, NEW YORK, ASSIGNOR TO BRANDES LABORATORIES, INC., OF NEWARK, NEW JERSEY, A CORPORATION OF NEW JERSEY.

DESIGN FOR A RADIOCABINET.

Application filed March 20, 1929. Serial No. 30,538. Term of patent 3½ years.

To all whom it may concern:

Be it known that I, AXEL G. ANDERSON, a citizen of the United States, residing at Jamestown, in the county of Chautauqua, and State of New York, have invented a new, original, and ornamental Design for a Radiocabinet, of which the following is a specification, reference being had to the accompanying drawing, forming part thereof.

The figure is a perspective view of a radiocabinet showing my new design.

I claim:

The ornamental design for a radiocabinet, as shown.

AXEL G. ANDERSON.
